UNITED STATES PATENT OFFICE

2,212,305

MEANS FOR CONTROLLING THE FLOW OF
GAS FROM A HOPPER, ETC.

Claude B. Schneible, Chicago, Ill.

Application September 21, 1938, Serial No. 231,085

9 Claims. (Cl. 209—133)

This invention relates to means for controlling the flow of gas from a hopper or a grate, etc.

The apparatus may be used to shut off one or more of a series of hoppers or grates not in use, at the time, to allow a definite saving in the fan or suction apparatus horsepower by controlling the flow of gases from said hoppers or grates, such as are used in foundry shake-outs or sand bins, or kindred installations in other fields.

10 An object of the invention is to provide a means of control of the gas flow as well as a support for the flask or other receptacle used to transport the material to the hopper or grate. The flow of gas is stopped until such time as it is necessary to dump material into the hopper and then opened to allow the flow of gas to carry off any dust particles, odors or obnoxious fumes that may be liberated during the operation without the waste of volumes of gases and the horsepower required to do so without this invention. The apparatus does not necessarily have to be constructed entirely as shown but may be adapted to a hopper or grate previously used.

In installations now in service, it has been necessary to provide a large volume of exhaust to meet the requirements, although only one or two of the series of hoppers were in use at one time. This invention allows the use of a smaller unit of the suction producing apparatus, as well as 30 any other equipment connected thereto, thus effecting a definite saving in installation cost as well as operating cost.

A further object of the invention is to provide apparatus upon which vessels containing, for example, sand or other material may be placed or shaken to remove it under the influence of suction while at the same time providing means for immediately closing the aperture after the dumping operation. A further object is to provide suction apparatus equipped with means of simple and sturdy construction whereby louvers are effectively employed for controlling a grill or dump opening, means being provided for maintaining the louvers in closed position. A further object is to provide means whereby a suction casing may be employed to receive material while providing means for closing the casing with a minimum of effort, resulting in a high economy in the suction-producing mechanism. Other specific objects and advantages will appear as the specification proceeds.

The invention is illustrated, in a preferred embodiment, by the accompanying drawings, in which—

55 Figure 1 is a side view in elevation of apparatus embodying my invention, the opening of the casing being shown closed; Fig. 2, a view similar to Fig. 1 but showing the top opening of the casing open; Fig. 3, a broken detail sectional view, the section being taken as indicated at line

3 of Fig. 2; Fig. 4, a broken top plan view; Fig. 5, a longitudinal sectional view, the section being taken as indicated at line 5 of Fig. 4; and Fig. 6, a plan view of a plurality of hoppers provided with damper controlled section pipes and with 5 louver apparatus embodying my invention.

In suction apparatus heretofore employed for the dumping of sand and other granular abrasive, it has been common to employ a suction apparatus with an open top and with a grill or net-work upon which the vessels containing the granular material may rest while the material is shaken out of them. The maintenance of the open top is an expensive operation since the suction device must be kept operating continuously. 10 In the present apparatus, I provide a casing with an open top but employed with rods which form the grill work upon which the vessels may be dumped, and louvers which turn with the rods and which, when the rods are turned in one position, afford a complete closure for the opening, and when the rods are turned in another position, an open casing, the rods themselves providing the grill work. Simple means are provided whereby the louvers may be maintained in closed 15 position and also whereby with a minimum of effort they may be allowed to drop to open position.

In the illustration given, A designates the casing; B, the louver structures; and C, the 20 mechanism for operating the louvers.

The casing A may be of any suitable construction. In the illustration given, it comprises a rectangular lower member or hopper 10 having inclined walls and being surmounted by a U-beam lower-supporting structure 11. A cross beam 12, in the shape of an inverted U-beam, extends across the middle of the casing, as shown more clearly in Figs. 4 and 5. A latch plate 13 is secured to the top of the U-beam frame 11, as 25 shown more clearly in Figs. 1, 2, 3, and 4. The plate is apertured at 14. If desired, a further structure may be employed below the frame 10 for receiving the sand. It is common to employ 30 a bin having inwardly converging sides providing a discharge over a receptacle or over a conveyor. Since, however, such structure forms no part of the present invention, and since such structure is well known, it is not herein illustrated. Any 35 suitable receiving receptacle or device may be 40 employed.

The louver structure B may be of any suitable construction. In the illustration given, hinge rods 15 have their ends journaled in openings 45 formed within the U-shaped channel frame 11, as 50 shown more clearly in Figs. 4 and 5. On the front side, illustrated in Figs. 1, 2, 3 and 4, rods 55 15 on the right side of the structure extend through the members 11 a short distance, and to the protruding ends of such rods are fixedly 60

secured depending link members 16. Likewise, the three rods 15 on the left side of the casing extend through the structure 11 on the opposite side of the casing and are provided with similar downwardly extending links 16. Fixed to each of the rods 15 is a louver vane 17. Since the vane 17 is fixed to the hinge rod 15, it must rotate with the hinge rod when the rod is manipulated as hereinafter described.

Any suitable means for operating the louvers may be employed. In the illustration given, the mechanism C comprises an actuating lever 18 equipped with a treadle plate 19, the lower end of the lever 18 being hingedly connected to a pivot bar 20. The bar 20 is pivotally carried by a pin 21, which is in turn supported by the casing 19. The opposite free end of the pivot lever 20 is pivotally secured to a pair of equalizer links 22. Pivotally secured between links 22 are links 23 and 24. Link 23 is connected by link 25 directly to the hinge rod 15, while link 24 is connected by link 26 directly to the convenient or adjacent hinge rod 15. The last mentioned hinge rods 15 are those closely spaced rods in the central portion of the apparatus and they lie directly below the cross bar 12. In order to cause the hinge rods to rotate in unison, I connect the series of links 16 on each side of the casing with a longitudinally extending link 27. In order to lock the louvers in closed position, as illustrated in Fig. 1, I provide the actuating lever 18 which extends through opening 14 of plate 13 with a locking notch 28 adapted to receive plate 14 when the member 18 is depressed.

Any suitable suction device may be employed within the casing A. In the illustration given, I provide a suction pipe 29 provided at its top side with a longitudinal opening 30, the opening being disposed below the cross beam 12 and sheltered by the depending louvers 17 supported below cross beam 12, particularly when the louvers are in open position, as illustrated more clearly in Fig. 5. The pipe 29 is closed at the forward end of the casing A but extends through the rear portion of casing A, as shown more clearly in Fig. 4. The pipe 29 extends to its suitable source of suction (not shown).

In the structure shown in Fig. 6, a plurality of hoppers or casings A are shown equipped with louver construction B of the type already described.

The suction pipes, however, are inclined within the hopper so that the opening in the pipe communicating with the interior of the hopper runs diagonally across the hopper. Through the use of the louver construction and the diagonal arrangement shown, an even suction may be maintained along the top of the casing. Dampers 33 are provided for each of the pipes 29 which communicate with manifold 34. By means of the damper, any of the hoppers can be cut off from suction or connected with suction manifold 34.

Operation

In the operation of the apparatus, assuming that the louvers are closed, as illustrated in Figs. 1 and 5, there is substantially no drain upon the suction mechanism. The louvers are maintained in closed position by the latch bar 18, the notch 28 of which engages plate 13, as illustrated more clearly in Fig. 1. When it is desired to dump sand or granular material into the casing, the operator simply presses the lever 18 toward the right of the casing so that notch 28 clears and permits the lever 18 to move upwardly. The

weight of the louvers 17 immediately causes the lever 18, and the other parts associated therewith, to assume the positions shown in Fig. 2. It will be observed that the louvers drop to the positions illustrated in Fig. 2, the two innermost louvers which are shielded by the cross beam 12 forming a triangular shield over the opening 30 of the suction pipe 29. In this arrangement, the hinge rods 15 which extend across the casing at spaced intervals provide a grill upon which the container of the granular material may be dumped and struck in order to free the container of the granular material. After the dumping operation, it is merely necessary for the operator to press the bar 20 downwardly, which he can readily do with his foot, the notch 28 of the bar sliding into engagement with the plate 13 and forming a latch therewith. In this operation, the outer end of pivot bar 20 moves upwardly causing the links 22, 23, 24, 25 and 26 to likewise move upwardly to the position shown in Fig. 1. The upward movement of link 25 causes the rod 15 fixed thereto to swing toward the right. The movement of this rod 15 causes a similar movement of the rods to the right thereof because of the connection through links 16 and common link 27. The upward movement of link 26 rotates the rod 15 attached thereto and this rod actuates at its other end through the medium of the connecting links 16 and 27, the three rods on the rear side of the casing, thus causing the louvers 17 carried thereby to swing to raised or closing position. Thus, by a very simple movement, the shutters are swung to closed position after the dumping operation and the drain upon the suction apparatus is discontinued.

It will be observed that instead of the open grill work formerly employed in such dumping operations where there is a constant drain upon the suction mechanism, I have provided extremely simple mechanism by which, with very slight effort, the operator can open the louvers, dump the containers, and close the louvers while going for the next load of containers. At the same time, a minimum of mechanism is provided, the hinge rods supporting the louvers providing the grill work for the dumping operation, and the depending louvers providing deflectors for the suction pipe outlet.

While in the foregoing description, I have set forth in detail certain apparatus which may be employed to carry out my invention, it will be understood that the apparatus may take many other forms and employ many other details which will be obvious to those skilled in the art, without departing from the spirit of my invention.

I claim:

1. In suction apparatus, a casing having an open top, a suction pipe within said casing, a plurality of hinge rods rotatably secured within said casing at the top thereof forming a grill extending across the top of said casing, louvers fixedly secured to said hinge rods and extending downwardly into said casing, and means for simultaneously rotating said hinge rods and releasably locking the same in closed position, said louvers swinging to open position when released from said locking means under their own weight.

2. In suction dump apparatus of the character set forth, a casing provided with an open top, a suction pipe within said casing and provided with an intake, and louvers hingedly secured within the top portion of said casing, at least two of said louvers being closely associated and providing when swung to lowered position a de-

reflector shield for the opening of said suction pipe intake.

3. In apparatus of the character set forth, a casing, a suction pipe therein provided with a top opening, hinge rods extending across said casing, two of said hinge rods being closely spaced together above the opening of said suction pipe, louver vanes secured to said hinge rods and adapted to be swung to upper and lower positions upon rotation of said hinge rods, the louver vanes of said closely spaced rods providing when in lowered position a baffle deflector over the opening of said suction pipe, and means for rotating said hinge rods.

15 4. In apparatus of the class set forth, a casing, a suction pipe supported therein and communicating with the interior thereof, hinge rods extending across said casing and rotatably supported thereby, a louver fixed at one end to each 20 of said rods and being urged by its weight downwardly to open position, link members connecting said rods, a link mechanism for actuating at least one of said rods whereby a plurality of the other rods is simultaneously actuated, said 25 actuating means being provided with latching mechanism whereby the rotatably mounted rods may be locked in raised position.

5. In apparatus of the character set forth, a casing provided with a top opening, a suction 30 pipe extending thereinto and provided with an opening in the top thereof, a plurality of rods extending across the top of said casing, some of said rods extending through the casing on one side thereof and some of said rods extending 35 through the casing on the opposite side thereof, links connecting the rod portions extending through the casing on each side thereof, two of said rods being closely spaced together above the opening of said suction pipe, louvers fixed to said rods, said louvers being wider than the space between said rods, and means for rotating said rods whereby the two said closely spaced rods rotate in opposite directions, the louvers of said closely spaced rods providing a V-shaped

baffle over said opening in said suction pipe when said louvers are moved to open position.

6. In suction dump apparatus of the character set forth, a casing provided with an open top, a suction pipe within said casing and provided with an intake opening extending longitudinally of the pipe, and louvers hingedly secured within the top portion of said casing, certain of said louvers providing a deflector shield for the opening of said suction pipe.

10 7. In apparatus of the character set forth, a casing, a suction pipe therein provided with an intake opening extending longitudinally of said pipe, hinge rods extending across said casing, louver vanes secured to said hinge rods, and means for rotating said hinge rods, said louver vanes providing a closure above said suction pipe when said louvers are swung to open position.

15 8. In apparatus of the class set forth, a casing, a suction pipe supported therein and communicating with the interior thereof, hinge rods extending across said casing and rotatably supported thereby, a plurality of louvers, each of which is fixed at one end to one of said rods, said louvers when swung to raised position being 20 in overlapping relation and tending to drop of their own weight to open position, and means for simultaneously rotating said rods to raise said louvers and to latch them in raised position.

25 9. In apparatus of the class set forth, a casing, a suction pipe supported therein and communicating with the interior thereof, hinge rods extending across said casing and rotatably supported thereby, a plurality of louvers, each of which has its end secured to one of said rods and 30 being urged by its weight downwardly to open position, link means connecting said rods, and a treadle member pivotally connected to said link means and adapted to rotate said rods to raise said louvers, said treadle member being equipped with means on said casing for latching said louvers in raised position.

35 CLAUDE B. SCHNEIBLE.
